UNITED STATES PATENT OFFICE.

MOSES G. COOK, OF LYNN, MASSACHUSETTS.

SPEEDOMETER.

1,194,144.

Specification of Letters Patent.

Patented Aug. 8, 1916.

Application filed December 17, 1913, Serial No. 807,227. Renewed January 15, 1916. Serial No. 72,371.

To all whom it may concern:

Be it known that I, MOSES G. COOK, a citizen of the United States, and residing at Lynn, in the county of Essex and Commonwealth of Massachusetts, have invented certain new and useful Improvements in Speedometers, of which the following is a full and exact description.

This invention relates to devices for revealing the speed at which a conveyance is moving, and has for its object the effecting of improvements whereby the speed can be more accurately disclosed; to means whereby the speed can be known to those too far away to distinguish the figures on its dial; and to improvements in details of construction hereinafter set forth.

Referring to the drawings forming part of this specification, Figure 1 is an elevation of a speedometer embodying my improvements, with one wall broken away. Fig. 2 is a side central sectional elevation. Fig. 3 is a sectional detail view. Fig. 4 is a detail view of other parts.

For indicating the speed registered by this speedometer, I prefer to employ a circular frame 1 mounted on a spindle 2 and adapted to carry several transparent sheets 3 of different colors. Such frame is stamped from sheet metal, as aluminum, and comprises a hub 4, spokes 5 and a rim 6. Where the sheets or plates 3 are composed of transparent celluloid, they can be more readily attached to said frame, than when of glass.

Said frame is adapted to be revolvably supported within a case 10, through each face 11 of which is a window 12 corresponding somewhat closely in general outline to a plate 3. For properly moving said index

frame 1, its spindle 2 is put in control of a shaft 15 which is rotated by power taken from moving parts of the automobile carrying the device, in any well known manner, said shaft being provided with a centrifugally actuated mechanism adapted to partially rotate said spindle. Such a centrifugally actuated mechanism which I have found best suited for the purpose, comprises two parallel disks 16 having fixed between

them at diametrically opposite points cross bars 17 serving both to rigidly join said disks and to provide more or less of the weights upon which centrifugal energy can act. Said disks 16 are also united by a pin 19 loosely penetrating their centers and rig-

idly held by the shaft 15. Slidable upon said shaft and slotted to avoid said pin, is a sleeve 20 having a radially projecting lug 21 from which extends a screw 22 carrying at its outer end a small cross arm 23 terminally engaging the radial slots 24 formed in said disks. Consequently, when under the influence of centrifugal energy the cross bars 17 and additional weights 18 swing said disks through a limited arc, the screw 22 and sleeve 20 are moved downward thereby a short distance. Upon a reduced upper portion 25 of said sleeve and retained thereon by a collar 26, is a second sleeve 27 bearing a rack 29 which meshes with a pinion 30 fixed upon said spindle 2. Hence, as said sleeve 20 rises and falls, said rack moves therewith and rotates said spindle and the frame 2 carried by the latter, but said rack-sleeve being rotatively supported by the sleeve 20, does not turn with the latter but remains in perfect mesh with said pinion. To insure the same, the rack-sleeve 27 is formed with two lugs 31 loosely embracing the guide rod 32. For counterbalancing said sleeves and connected parts, a second pinion 33 is mounted on the spindle 2, and a tubular weight 34 provided which carries a rack 35 meshing with said pinion 33. A fixed rod 36 slidably guides said weight, and lugs 37 and fixed rod 38 to keep the same from turning and throwing said rack out of mesh with the pinion 33. For returning said disks and connected parts to their positions of rest, a tension spring 39 has its ends attached to a collar 40 on the shaft 15, and to an adjusting member 41 on one of the weight-bars 17. By properly adjusting the tension of this spring, the centrifugally operated devices are adapted to turn the spindle 2 and frame 1 accurately to designate the speed of the automobile. A more delicate adjustment for the purpose is given by the screw 22 which rotatably bears the cross arm 23. By turning said screw in or out of its boss or lug 21, said cross arm is made to bear upon shorter or longer radii of the disks, and hence to correspondingly affect the power transmitted by the disks to the rack bar and indicator frame 1.

In order that the slots 24 shall not affect the centrifugal action of the weights 17, 18, a second slot 42 is cut in each disk diametrically opposite said slots 24; and in order that these slots 24 and 42 shall be incapable

of affecting the centrifugal action, two other slots 43 are formed in each disk diametrically opposite to each other and at points ninety degrees away from the first-named slots.

5 A screw 44 is tapped through a cross bar 17 to be met by the boss 21 at one limit of the disks' movements.

In Fig. 1, the frame 1 is represented as displaying two differently colored plates 3 10 between the two windows 12 (Fig. 2) one color being selected to designate one range of speeds, and the other another range. I prefer to have "white" or clear transparent designate a range of speeds between zero and 15 10 miles per hour; to have green designate between 10 and 20; yellow between 20 and 30; red, between 30 and 40, while a completion of the circle to present white again designates between 40 and 50 miles an hour.

20 If nothing but a single color can be seen through the window, then the full limit of speed associated with such color is designated. That is, if only red can be seen, a speed of 40 miles an hour is indicated, since 25 red stands for speeds between 30 and 40 miles per hour. If, however, two colors are exposed, as in Fig. 1 which show the conventional lines representative of green and yellow respectively, then the speed indicated is 30 past the higher limit of the green (20) and partly in the yellow whose lower limit is 20. If the spoke 5 is positioned at the center of the window 12, the speed indicated is 25 miles per hour, but in the position shown in 35 Fig. 1, the speed is but 28 miles an hour. For the readier perception of the units thus referred to, the upper edge of the window 12 is formed with serrations nine in number, each carrying its proper numeral.

40 What I claim is:

1. A speedometer comprising a rotary member provided with differently colored sections designed to be indicative of different ranges of speed, means controlled by the 45 speed of the conveyance carrying the speedometer for turning said member, and a case inclosing said member, said case having a window substantially equal in dimensions to one of said sections, an edge of said window 50 being formed with nine serrations each bearing one of the nine digits.

2. A speedometer comprising an indicating means, a vertical shaft adapted to be revolved by the body whose speed is to be 55 measured, a rotary member having its axis of rotation transverse to and carried by said shaft, weights carried by said member, a sleeve slideable on said shaft, a rack carried by said sleeve, a spindle connected with said 60 indicating means, two pinions on said spindle, one meshing with said rack, and a second weighted rack meshing with the other

of said pinions for counterweighting said sleeve.

3. A speedometer comprising an indicating means, a shaft adapted to be revolved by the body whose speed is to be measured, two parallel disks having a common axis transverse to and carried by said shaft, two oppositely disposed heavy cross bars rigid with 65 said disks, and means whereby the centrifugally engendered partial rotation of said disks on their common axis is communicated to said indicating means.

4. A speedometer comprising a rotative 75 indicating means, a shaft adapted to be revolved by the body whose speed is to be measured, two parallel disks having a common axis transverse to and carried by said shaft, two oppositely disposed heavy cross 80 bars rigid with said disks, and two oppositely disposed weights on the outer surface of each disk, and means whereby the centrifugally engendered partial rotation of said disks on their common axis is communicated to said 85 indicating means.

5. A speedometer comprising a rotative 90 indicating means, a shaft adapted to be revolved by the body whose speed is to be measured, two parallel disks having a common axis transverse to and carried by said shaft, weights carried by said disks at opposite points of their peripheries, a sleeve slideable on said shaft, a radially disposed screw carried by said sleeve, a cross arm terminally 95 supported by said screw, said disks having each a radial slot receiving an end of said cross arm, and means for turning said indicating means actuated through the reciprocation of said sleeve.

6. A speedometer comprising an indicating means, a shaft adapted to be revolved by the moving body whose speed is to be measured, a sleeve slideable on said shaft, two parallel disks having a common axis transverse to and carried by said shaft, oppositely disposed weights carried by said disks, four uniformly disposed radial slots being formed in the periphery of each disk, means engaging two of said slots whereby the partial turn of said disks on their axis slides said sleeve on said shaft, yielding means acting on said disks in opposition to the effect of centrifugal energy thereon, and means whereby the movements of said sleeve are 105 adapted to actuate said indicating means.

In testimony that I claim the foregoing invention, I have hereunto set my hand this 16th day of December, 1913.

MOSES G. COOK.
